(57) **CLAIM**

I claim the ornamental design for a framework connector, as shown and described.

DESCRIPTION

FIG. 1 is a perspective view of the framework connector, as viewed from the front, top, and left side thereof.

FIG. 2 is a front elevation view of the framework connector, the rear elevation view being a mirror image thereof, and wherein the top plan view and the bottom plan view of the framework connector are mirror images of each other and are identical to the front elevation view; and,

FIG. 3 is a left side elevation view of the framework connector, the right side elevation view being a mirror image thereof. The dashed lines in the drawings are for illustrative purposes only and form no part of the claimed design.
